DRAINBOARD

Harry N. Wheeler and Tillman E. Wheeler,
Birmingham, Ala.

Application October 2, 1943, Serial No. 504,779

7 Claims. (Cl. 4—166)

This invention relates to a drain board which shall be readily adapted to be attached to and detached from an ordinary bathroom lavatory and which shall afford means for light laundering operations as well as converting the lavatory to various cleaning operations other than its primary use.

Dwellers in small apartments having no laundering facilities often have need for washing and drying small articles of apparel, and for other washing and cleaning which cannot be readily carried out in the ordinary lavatory. In accordance with our invention we provide a light, flexible, water resistant drain board which may be mounted on the ordinary lavatory and securely held in place thereon, and which converts the lavatory to a sink with a suitable drain board, and includes means for holding articles to be dried.

A device embodying features of our invention is illustrated in the accompanying drawing, forming a part of this application, in which

Fig. 1 is a plan view showing our improved drain board mounted on a lavatory.

Fig. 2 is a sectional view taken along the line II—II of Fig. 1 and

Fig. 3 is a plan view showing the drain board for attachment to a corner lavatory.

Referring to the drawing for a better understanding of our invention we show a lavatory embodying a table portion 10 and a bowl 11 with the usual splash board 12 at the rear. As is usual there is provided a ridge 15 extending around the table portion 10 to cause water splashed from the bowl to drain back into it. Faucets 13 and 14 are mounted to extend upwardly through the table portions 10 and may be provided with discharge spouts 16 and 17 which overhang the bowl 11 and which also may extend downwardly below the level of the ridge 15 on the table portion 10. This latter feature, as will later be seen, is not necessary to our invention as our improved drain board may be employed with faucets of any design, such as with a single mixing faucet. The bowl is provided with the usual drain outlet 20 which may be controlled in any suitable manner, not shown.

Our improved detachable drain board is comprised of a sheet of material 18 which should be stiff enough to stand the service for which it is intended, and flexible enough to be sprung under the discharge spouts 16 and 17, in placing it on the lavatory. Accordingly it may be made of metal, plywood, composition board, plastic materials of various kinds, and others which will suggest themselves to those skilled in the art. The

drain board is provided with an opening 19 over the bowl 11 which opening is made preferably wider than the bowl to permit some lateral adjustment of the drain board on the lavatory to avoid adjacent articles or walls in the room in which it is located. A plurality of drain grooves 21 are provided in the surface of the drain board all of which lead into the opening 19. Around the ends and front of the drain board, we provide slots 22 to afford a means for hanging small articles to dry, such as stockings, handkerchiefs and the like.

It will be seen by reference to the drawing that the opening 19 is so formed as to provide a relatively narrow strip 23 at the rear which, in the case of a round bowl such as shown in Fig. 1 may overhang a portion of the bowl and is slid under the discharge spouts 16 and 17 to rest on the table portion 10 of the lavatory. Where the discharge spouts 16 and 17 extend below the level of the ridge 15, they engage the strip 23 and hold the drain board in place. For that reason it will be seen that the material from which the drain board is made should be flexible enough to be bent and slid under such discharge spouts. The strip 23 is also provided with a plurality of notches 24 along the back edge which are adapted to engage the faucets 13 and 14 and prevent lateral displacement of the drain board when in use.

Where the discharge spouts 16 and 17 do not extend downwardly as low as shown in Fig. 2, other means must be provided for attaching the drain board to the lavatory. In order to accomplish this we may provide spring clips 26 which may be attached at 27 and 28 to the rear strip 23 of the drain board and hooked around the faucets 13 and 14. We show the drain board as being provided with a plurality of small holes 29 along the rear strip 23 through which the clips 26 may be attached to accommodate various spacings of the faucets 13 and 14.

In Fig. 3 of the drawing we show a modified form of our invention which is adapted for a corner lavatory. Such a lavatory may comprise a table portion 31 having a corner splash board 32 at the rear with faucets 34 and 36 extending upwardly through the table portion and with a single mixing discharge spout 37 overhanging the bowl 39. In accordance with this modification, the drain board 41 is provided with rear corners cut away at 42 and 43 to fit into the recess formed by the splash board 32. This causes the end slots 44 to be shorter than the end slots 22 shown in Fig. 1. In all other respects the drain board 41

is substantially the same as that shown in Figs. 1 and 2.

We show in Fig. 3 a further modified form of attaching the drain board to the lavatory. In accordance with this modification, we provide a flexible member, such as a cord 46, which is permanently attached to one end of the drain board and which is passed under the bowl 39 as indicated in dotted lines, to the rear of the drain conduit 47 to be secured in a notch 48 at the opposite end of the drain board. Such securing means is particularly adapted for lavatories having the faucets so positioned that the clips 26 may not be used to advantage.

From the foregoing it will be apparent that we have devised an improved drain board which may be readily attached and detached from an ordinary lavatory, which is adapted to render the lavatory more adaptable for various cleaning operations.

While we have shown our invention in but two forms, it will be obvious to those skilled in the art that it is not so limited, but is susceptible of various other changes and modifications, without departing from the spirit thereof, and we desire, therefore, that only such limitations shall be placed thereupon as are specifically set forth in the appended claims.

What we claim is:

1. In combination with a lavatory having a table portion and a bowl with faucets mounted on the table portion, a detachable drain board overhanging the table portion and having an opening therein over the bowl, and detachable means cooperating with the back of the board and the faucets to secure the drain board on the bowl.

2. In combination with a lavatory having a table portion and a bowl with faucets mounted on the table portion and having discharge spouts overhanging the bowl, a detachable drain board overhanging the table portion and having an opening therein over the bowl, and a strip at the rear of the bowl adapted to be engaged behind the discharge spouts, said discharge spouts extending downwardly below the level of the table portion of the lavatory to engage the strip and hold the drain board in place.

3. In combination with a lavatory having a table portion and a bowl with faucets mounted on the table portion and having discharge spouts overhanging the bowl, a detachable drain board overhanging the table portion and having an opening therein over the bowl, and a strip at the rear of the bowl adapted to be engaged behind the discharge spouts, said discharge spouts extending downwardly below the level of the table portion of the lavatory to engage the strip and hold the drain board in place, there being notches formed in the back of the strip to engage the faucets and prevent lateral displacement of the drain board.

4. A detachable drain board for attachment to a lavatory having a table portion and a bowl with faucets mounted on the table portion and having discharge spouts overhanging the bowl, comprising a flexible water resistant member adapted to 10 rest on the lavatory and overhang the table portion and having an opening therein to fit over the bowl with a strip along the rear behind the discharge spouts of the faucets, and flexible securing means for detachably connecting the drain board to the bowl.

5. A detachable drain board for attachment to a lavatory having a table portion and a bowl with faucets mounted on the table portion, comprising a flexible water resistant member adapted to rest on the lavatory and overhang the table portion and having an opening therein to fit over the bowl with a strip along the rear, notches formed in the rear of the strip to engage the faucets on the table portion, and flexible securing means for 20 attaching the drain board to the bowl.

6. A detachable drain board as set forth in claim 5 in which the flexible securing means comprises springs having their ends secured to the strip at the rear of the drain board and disposed 30 to hook behind the faucets.

7. A detachable drain board as set forth in claim 5 in which the flexible securing member is secured near one end of the drain board and is adapted to be passed under the lavatory and 40 secured near the other end to hold the drain board in place.
